FLUID CONTROL VALVE FOR TURBODRILL

Sabin J. Gianelloni, Jr., P.O. Drawer 1870,
Baton Rouge, La.

Original application July 18, 1957, Ser. No. 672,722, now
Patent No. 2,963,099, dated Dec. 6, 1960. Divided
and this application Aug. 1, 1960, Ser. No. 46,602
2 Claims. (Cl. 175—26)

This invention relates to a turbodrill and is a division
of application Serial No. 672,722, filed July 18, 1957, now
Patent 2,963,099.

A turbodrill consists essentially of a tubular turbodrill
body usually suspended from a drill pipe which applies
mud or other fluid to a turbine which, in turn, drives a
bit. Control heretofore has been by varying the total
quantity of mud supplied to the turbodrill body.

It is the general object of the invention to provide an
improved turbodrill.

Another object is to provide improved means for con-
trolling a turbodrill.

It is another object to provide an improved turbodrill
wherein the quantity of fluid supplied to the driving tur-
bine is controlled automatically so as to maintain a fairly
uniform speed.

A further object is to provide an improved turbodrill
wherein a substantially constant quantity of mud may be
supplied to the drill body and the quantity actually pass-
ing through the turbine determined in accordance with
the power needs at a particular constant speed.

Another object is to provide a turbodrill with means
for limiting the speed of the turbine to a constant speed
in accordance with the need for varying power torque of
a bit.

Another object is to provide a turbodrill wherein a bit is
regulated so as to be maintained at a speed below a pre-
determined limit.

A more specific object is to provide improved methods
for controlling the quantity of mud passing through the
turbine for driving the same.

Another object is to provide a turbodrill having means
for conducting all of the mud supplied to the body to the
bit while only a portion thereof passes through the tur-
bine for driving the bit.

Still another object is to provide a turbodrill having
means for controlling the action of the turbine in accord-
ance with the power needs for a bit to maintain a constant
predetermined speed.

A further object it is provide a turbodrill with means
for controlling the quantity of a fluid such as mud to the
turbine in accordance with the thrust on the bit in the
hole.

A still further object is to provide a turbodrill with
means for controlling the quantity of mud to the turbine
in accordance with the torque imparted to a bit.

Other objects and various features of novelty and in-
vention will be pointed out hereinafter or will become
apparent to those skilled in the art.

Briefly stated, in a preferred form of the invention,
there is a turbodrill body and within the body there is a
rotatable shaft which is shown as an integral part of the bit
shaft. This bit shaft is supported on suitable bearings,
one being a thrust bearing and as many radial bearings
as may be required. A fluid mud turbine in the drill body
drives this shaft and rotates the bit. The mud, after pass-
ing the turbine, is conducted to the bit and functions in
the usual fashion. Generally speaking, the turbine of a
turbodrill has been controlled heretofore merely by con-
trolling the quantity and pressure of the mud reaching the
drill body. In the improved turbodrill, part of the mud
entering the body may pass directly to the bit and part
may first pass through the turbine and then to the bit.

2

The invention relates mainly to the control of the turbine
and the improved functioning of the turbodrill.

The improved turbodrill will be shown and described
as embodied in a more or less schematic or kinematic
form, rather than in a structurally accurate and complete
design.

In the drawings, which show, for illustrative purposes
only, preferred forms of the invention:

FIG. 1 is a fragmentary use of a central vertical sec-
tional view through a turbodrill illustrating features of the
invention;

FIG. 2 is a sectional view, taken substantially in the
plane of the line 2—2 in FIG. 1;

FIG. 3 is a fragmentary view similar to FIG. 1 illus-
trating another modification;

FIG. 4 is a sectional view, taken substantially in the
plane of the line 4—4 in FIG. 3; and

FIG. 5 is a sectional view, taken substantially in the
plane of the line 5—5 of FIG. 3.

In the form shown in FIG. 1 there is turbodrill body 5
secured to and preferably suspended from a drill pipe
6 which, in the form shown, supplies mud to the tur-
bodrill. Within the body 5 is a hollow shaft 7 which, as
shown, is an integral part of the shaft carrying a bit 8 of
any usual or desired form. The shaft 7 is supported by a
thrust bearing 10 which may consist of rubber or other
material, such as the discs 11—11 secured to the body 5
and coating discs 12 secured to the shaft 7, and the thrust
bearing 10 is arranged to have passages therethrough
such as the passages 13 for the free passage of fluid such
as mud entering through the drill pipe 6.

Within the body 5 is a turbine for driving the shaft 7.
This turbine, as illustrated, consists of rotor blades 14
carried by the shaft 7 and stator blades 15 carried by the
body 5. Normally, mud entering through the pipe 6
passes down through the body 5 and through the thrust
bearing passages 13 and the turbine blades. Thus, by
means of the turbine blades, the shaft 7 is rotated, and of
course, the bit 8 is rotated with it. A lower radial bear-
ing 16 supports the shaft 7 at the bottom, and there may
be as many other radial bearings as may be required.

It should be noted that the turbine blades 14 in a par-
ticular horizontal plane are attached to a separate ring
14a as illustrated by the cross hatching in a different direc-
tion for successive rings in FIG. 1, and each of the rings
14a is secured to the shaft 7 by means of a key 14b ex-
tending vertically as shown in FIG. 1.

Mud, after being passed through the turbine, enters
passages 17 in the lower end of the shaft 7, which passages
connect with the central bore 18 through the shaft leading
to the bit 8 in the usual fashion. In turbodrills of the
prior art, the speed of the bit 8 has been controlled by
controlling the volume and pressure of mud issuing from
the drill pipe 6. These prior methods, however, have
been somewhat unsatisfactory as a control, particularly
when the bit encounters different formations.

By the above mentioned prior method of control, the
bit will run at excessive speeds through certain formations
and at a much reduced speed through other formations.
This invention relates particularly to the method of and
means for controlling the speed of the turbine. In the
form of the invention shown in FIG. 1, this is done by
regulating the quantity of mud passing through the turbine
without limiting the total flow of mud to the bit, which
total quantity is often required for proper drilling.

In the form illustrated in FIG. 1, the mud entering the
body 5 through the drill pipe 6 may device and go through
two passages, one passage 18 by-passes the turbine and the
second passage 19 leads directly to the turbine. By con-
trolling the flow of fluid through the upper end of the by-
pass passage 18, the part of the fluid through the passage
19 and the turbine is controlled so as to control the tur-

bine speed. When the upper end of the passage 18 is closed entirely, all of the mud entering the body 5 passes through the passage 19 and goes directly to and through the turbine for driving the same. When the upper end of the passage 18 is about wide open, much of the mud passes through the passage 18, thus by-passing the turbine; therefore, the turbine runs at some minimum speed.

To maintain the speed of the turbine and the bit 8 approximately constant, means is provided within the body 5 for controlling the by-pass passage 18. Such means, in the form illustrated in FIG. 1, will now be described in detail.

A stuffing box 20 is provided at the upper end of the body 5 through which the drill pipe 6 extends and in which it is slidably. The body 5 has an abutment bushing 21 secured thereto (part of the stuffing box 20), and the bottom of the drill pipe 6 forms a valve carrier 22.

This valve carrier 22 at the bottom of the drill pipe 6 is a continuation thereof and has a shoulder flange 23, and a compression spring 24 is interposed between the abutment bushing 21 and the shoulder 23 at the bottom of the drill pipe 6. Thus, the entire weight of the turbodrill is carried by the drill pipe 6 through the compression spring 24.

The valve carrier 22 has passages 25 therein for the passage of fluid from the drill pipe 6 to the body 5 and to the passage 19 leading to the turbine, as heretofore described. This valve carrier 22 carries a valve member 26 to coact with a valve seat 27 on the upper end of the tubular shaft 7.

As best seen in FIG. 1, the valve member 26 is a separate unit, preferably. This arrangement permits replacement of the valve member 26 with a maximum of efficiency, since it is only necessary to withdraw a pin 26a. As illustrated, the pin 26a fits loosely in apertures 26b because it is impossible for the pin 26a to come out of the apertures 26b due to the close spacing with the inside wall of the body 5.

Now, it may be seen that as a driller advances the drill pipe 6, the flange 23 acts against a limit flange 23a, at which point the valve 26 is substantially closed to permit minimum bleed through passage 18. Therefore, under this operation, most of the fluid is forced through the turbine.

The thrust on the bit is caused by the weight of the turbodrill body and drill and any other parts carried thereby. All parts of the drill body and the bit are suspended on the drill pipe through the spring 24.

When the turbodrill is working properly, the valve 26 is about closed and nearly all of the mud passes through the turbine to drive the bit. The speed is kept normal by the amount of weight carried by the turbodrill set up during normal drilling.

By "normal" drilling it is meant that the speed is anything less than runaway speed that conventional turbodrills encounter when little or no resistance is met by the drill. As long as the driller follows the turbodrill by lowering the drill pipe as drilling proceeds, the drill will continue to operate as described.

If the driller fails to lower the drill pipe, the drill continues downward and the spring 24 starts to compress. During this time the drill operates against progressively less resistance because it is not being advanced at a speed commensurate with the cutting of the material being drilled. Therefore, the speed normally would increase, but during this time the valve seat 27 is drawing away from the valve member 26 and more and more mud is by-passed through the hollow shaft 7. Therefore, the speed of the turbine and bit is decreased.

Even when the bit is drilled down so as to hang freely, the speed will be kept within normal limits because of the small amount of mud that will be permitted to pass through the turbine. Thus, instead of controlling the quantity of mud reaching the turbine, by means of the speed of the bit, as in the form of the invention claimed

in the parent application S.N. 672,722, the quantity of mud reaching the turbine is controlled by the thrust on the bit, as illustrated in FIG. 1. Therefore, when the turbine is suspended above the bottom, the spring 24 is compressed and the valve 26 is lifted from the seat 27 permitting the maximum by-pass of the mud.

As best seen in FIG. 2 of the drawings, the valve carrier 22 is substantially square in cross section, and the upper end of this valve carrier 22 is threaded onto the lower end of the pipe 6, as illustrated by the numeral 28 in FIG. 1.

In the modified form shown in FIG. 3, the quantity of fluid for driving the turbine is controlled not by the speed nor the actual hanging position of the turbodrill, but by the torque produced during the drilling operation. In the form shown in FIG. 3, the turbodrill body 5a has a bushing or gland 30 through which a drill pipe 6a extends and is rotatable. This drill pipe 6a extends down into the body 5a and has lateral passages 31-31 for conducting fluid mud out of the pipe 6a into the body 5a and down to the turbine blades 14-15 of the same type similar to that heretofore described. The shaft 7a passes through the thrust bearing 10 and has the passages 17-17 for conducting fluid into the passage 18 and to the bit the same as explained already above.

The upper end of the shaft 7a (which is tubular) has a valve seat 32, and the lower end of the drill pipe 6a carries a vertically movable valve member 33 to cooperate with the valve seat 32. This valve member 33 may have a screw cam 34 secured therein, the ends of which fit in vertical grooves 35-35 in the sides of the body 5a.

The end of the drill pipe 6a is formed with bias grooves 36 for receiving the pin 34, so that upon relative rotation between the body 5a and the drill pipe 6a, the valve 33 will be moved up or down so as to open or close the valve seat 32, and thus control the quantity of mud which by-passes the turbine.

To utilize and control the relative rotation between the body 5a and the drill pipe 6a, it is preferable to employ a resilient means such as a rubber sleeve-like member 37 secured at the lower end of the drill pipe 6a as indicated at 38 and at the upper end of the body 5a as indicated at 39. The amount of rotation between the body 5a and the drill pipe 6a is limited by shoulders 40-40 on the body 5a and the drill pipe 6a (FIG. 4).

When the bit (not seen in FIG. 3) is not encountering heavy formation, there is little or no relative rotation between the casing 5a and the drill pipe 6a, and the valve 33 will be in its wide-open position, as shown in FIG. 3. Then most of the mud passing down through the drill pipe 6a will pass through the valve seat 32 and then down the bore 18 directly to the bit. However, when the bit strikes the heavy formation, additional torque is set up in the turbine by reason of the fact that the shaft 7a tends to hold back due to the engagement of the bit with the hard formation, and the body 5a tends to rotate in the opposite direction, that is, in a clockwise direction viewed from the bottom.

This clockwise motion of the body 5a causes the cam 34 in the valve to move in the bias slot 36 and lower the valve 33 down towards its seat 32. When the maximum torque is encountered, the valve 33 will be substantially closed and substantially all of the mud will pass through the passage 19 directly to the turbine, and little or none of the mud will be by-passed through the valve seat 32.

In all forms of the invention shown and described, all of the fluid mud that passes down through the drill pipe reaches the bit through the turbine or by being by-passed directly to the bit through the hollow shaft. In any event, the rotation of the turbine is controlled and held fairly constant, not in accordance with the quantity of mud pumped down or its pressure, as in the prior art, but in accordance with the controlling factors which may be referred to as the conditions encountered by the bit, which

include the pressure against the bit, the torque variations as well as the rotational speed of the bit.

In all cases, the speed of the bit is regulated. With a properly controlled speed of the bit and a full flow of mud thereto assured, wear of all parts is reduced to a minimum and the necessity for bit changing or other servicing is reduced to a minimum. Thus, the overall efficiency of the turbodrill will be increased.

While the invention has been described in considerable detail and preferred forms illustrated, it is to be understood that various changes and modifications may be made within the scope of the invention, as defined in the appended claims.

I claim:

1. In a turbodrill, 15
a drill body,
a tubular drill shaft concentrically mounted in said body,
a bit on said shaft having means to receive mud through said shaft,
turbine means coupled to said body for driving said shaft,
a drill pipe for conducting mud to said drill body, concentrically mounted to said drill body, 20
passage means within said drill body and drill shaft for conducting mud from said drill pipe to said turbine and to said tubular shaft and bit,
valve means coupled to said drill shaft and drill body

5

cooperating with said passage means for controlling the flow of mud into said tubular shaft so as to bypass said turbine,
said drill body and said drill pipe being mounted for limited relative rotation,
said valve means being responsive to a change in rotation of said drill body relative to said drill pipe,
said turbine means responsive to the torque developed by the bit in the formation being drilled for rotating said drill body relative to said drill pipe.

2. In the turbodrill of claim 1, 10
in which said valve means closes to conduct mud to said turbine when said torque increases,
said valve means including cam means actuated by relative rotation of said drill body and drill pipe to change the said valve means.
